UNITED STATES PATENT OFFICE.

OLAVIS O. VICK, OF BEAR RIVER, MINNESOTA.

PERMUTATION-PADLOCK.

1,186,713.

Specification of Letters Patent. Patented June 13, 1916.

Application filed August 13, 1914. Serial No. 856,675.

To all whom it may concern:

Be it known that I, OLAVIS O. VICK, a citizen of the United States, residing at Bear River, in the county of St. Louis and 5 State of Minnesota, have invented certain new and useful Improvements in Permutation-Padlocks, of which the following is a specification.

This invention relates primarily to permutation padlocks, and has particular reference to permutation or keyless padlocks.

As the principal object, this invention contemplates provision of a padlock of this character which shall consist of the 15 smallest number of working parts and be of the simplest possible construction consistent with effective operation.

As a more particular object, this invention aims to provide a keyless padlock which 20 shall be operated by disk tumblers secured to suitable dials with the use of a single resilient member in novel operation therewith.

An object of equal importance with the 25 foregoing is to provide a permutation padlock in which the movable parts may be readily separated in order to readjust or vary the permutations of the dials or to otherwise insure the proper working order 30 thereof.

The above and additional objects are accomplished by such means as are illustrated in the accompanying drawings, described in the following specification and then more 35 particularly pointed out in the claims which are appended hereto and form a part of this application.

With reference to the drawings, wherein I have illustrated the preferred embodiment of my invention as it is reduced to practice, and throughout the several views of which like characters of reference designate similar parts, Figure 1 is a side elevation of an improved embodiment of the padlock, parts being broken away to show the shackle in locked position. Fig. 2 is a longitudinal sectional view showing the shackle in unlocked position. Fig. 3 is a bottom plan view of the padlock as a whole. Fig. 4 is a detail elevation of the carriage and dial. Fig. 5 is a top plan view of the carriage with the dials and tumblers positioned therein. Fig. 6 is a bottom plan of the locking bolt and tumbler plate. Fig. 7 is an elevation of one of the dials and the disk carried by the same.

Proceeding now with the description of the drawings, it will be seen that the padlock is of the customary appearance and consists mainly of the usual inclosing body portion 10 here illustrated as of elongated shape with rounded corners provided with the side walls 11 and the integral top plate 12, the latter being suitably apertured adjacent each extremity to provide for the pivoting of the shackle 13 between ears 14 formed on the body casing and to also provide for the entrant or locking end 15 of the shackle which is suitably cut away as at 16 to provide for the entrance and retention of the 70 longitudinally slidable locking bolt 17.

A removable carriage 18 is adapted to close the lower open end of the casing 10 and to serve as the support for the locking bolt 17 in order that the latter may slidably 75 operate in conjunction with the permutation disks and tumbler disks also revolvably supported by the carriage 18. As clearly shown in Fig. 5, this carriage has formed in one end the beveled recess 19 in order to 80 provide a space for the leaf spring 20 which as shown in Fig. 2 is secured to the wall 11 at the same end of the casing 10 to which the shackle 13 is pivoted, said spring acting in conjunction with the cut out portion 21 85 formed in the locking bolt 17 and normally tending to hold said locking bolt outwardly in the position illustrated in this figure. The sides of the carriage 18 are also cut away for a short space inwardly to provide 90 working recesses for the permutation dials and tumbler disks 22 and 23 respectively, each of the latter being secured concentrically to one of the former by any suitable 95 means such as the pin or rivet 24 and each pair of such dials being revolvably mounted upon the integral pivot 25 of the carriage 18 in such manner that while the smaller tumbler disk is retained wholly within the recess 19' the larger permutation dial projects through the opening 26 formed in the body of the carriage 18 and communicating with the larger recess so as to render manual 100 operation of these permutation disks easy 105 of accomplishment.

Both the permutation dials and the tumbler disks are formed with suitable indentations 27 and 28 respectively which answer the purpose of ratchet teeth and both dials and disks being formed with the comparatively larger indentations 29 and 30 respectively which serve a purpose to be here-

inafter more fully described. It will be understood in this connection that the pairs of disks mounted on opposite sides of the carriage 18 in their respective recesses are 5 loosely positioned upon the pivot pin 25 in order to be readily removable therefrom when the carriage 18 is withdrawn from the casing 10.

A tumbler plate 31 having the upturned 10 portion 32 projecting through the locking bolt 17 and secured therein is positioned in spaced and parallel relation to such locking bolt as clearly shown in Figs. 2 and 6 and 15 as will readily be seen upon an inspection of these figures is adapted to slide upon the reduced top 33 of the carriage 18, to abut the shoulder 34 formed by the raised portion 35 of said top upon which the locking bolt 20 is slidably supported. This tumbler plate 25 coacts with the tumbler disks 23 by means of the lateral wing portions 36 which abut 25 the indentations of such disks and by thus 30 withstanding the action of the leaf spring 20 normally prevent the withdrawal of the locking bolt 17 from the cut away portion 16 formed in the free end of the shackle.

From the foregoing detailed description, it will be understood that the operation of the improved permutation padlock is as follows: With the device in operative assembled position as illustrated in Fig. 1 all that 30 remains to be done in order to release the locked shackle is so to rotate the permutation dials 22 as to bring the larger indentations 35 of the tumbler disks into the position illustrated in Fig. 2, such rotation being aided by the notches or indentations 27 of the permutation dials acting in conjunction with a groove 37 or other indicating mark 40 which is preferably positioned as shown in Fig. 3 upon the bottom of the carriage 18, the larger indentations 29 of these dials serving as the initial points from which to 45 count the predetermined number of notches or half notches which must be turned either to the right or left from the indicating mark 37 which will effect the similar and parallel position of the large indentations 30 formed in the tumbler disks which are rotated with the dials in order to allow the tension of the spring 20 to draw the locking bolt 17 outwardly of the casing 10 and consequently withdraw it from its locking position in the 50 cut out portion 16 of the shackle, such withdrawal movement of the bolt it will be readily understood being permitted by the entrance of the winged portions 36 of the tumbler plate which had hitherto resisted such movement into the large notches 30 55 of the tumbler disks which as above set forth are properly positioned to receive the portions 36. It will be noted in this connection that before the permutation dials can be properly manipulated, the bolt 17 60 must be inwardly pressed against the spring 65

20 in order to obviate pressure of the wing portions of the dog or tumbler plate 31 against the indentations 28 of the tumbler disks, such pressure being normally assured by the spring 20 for normally preventing 70 manual operation of the permutation disks.

While in the foregoing however, I have thus illustrated in the drawings and described in the specification such combination and arrangement of elements as constitute 75 the preferred embodiment of my invention, I desire to emphasize the fact that I may make such minor changes in the matters of proportion and degree, in later adaptations of my device as shall not alter the spirit of 80 my invention as defined in the appended claims.

What I claim is:

1. In a permutation pad lock, a casing, a pivoted shackle, a locking bolt for said shackle, a plurality of revolute dials, means for supporting said dials, a tumbler plate carried by said bolt and having wing portions, a tumbler disk carried by each dial and provided with a recess to receive one 90 of the wing portions of said tumbler plate when in one position, and means for forcing said bolt outwardly and moving said wing portions into said recesses.

2. In a permutation lock, a casing, a carriage removably positioned in said casing, permutation dials pivotally mounted upon said carriage, tumbler disks concentrically mounted with each of said dials, a spring retained locking bolt slidable between said 100 dials, and a tumbler plate normally abutting said tumbler disks to prevent withdrawal of said locking bolt.

3. The combination of a slidable locking bolt, resilient means normally tending to withdraw said bolt, revolute permutation dials to either side of said bolt, tumbler disks revolute with said permutation dials, and means carried by said bolt to abut the peripheries of said tumbler disks against 110 the action of said resilient means.

4. The combination of a locking bolt, resilient means normally tending to withdraw said bolt, revolute permutation dials to either side of said bolt, tumbler disks revolute with said permutation dials, means carried by said bolt to abut said tumbler disks against the action of said resilient means, and means formed in each of said tumbler disks to accommodate first said 120 means and to release the tension of said resilient means upon proper manipulation of said dials.

5. A permutation lock including a casing, a shackle pivoted in said casing, a removable carriage positioned in said casing, permutation dials revolutely mounted on said carriage, tumbler disks concentric and revolute with said dials, said disks having elongated notches therein, a locking bolt for 125 130

5 said shackle slidably positioned between said dials, resilient means carried by said casing and normally tending to withdraw said bolt from its locked position, and means carried by said bolt abutting said disks and resisting the action of said resilient means, said abutting means being also movable in said notches to allow the withdrawal of said bolt.

10 6. A permutation lock including a casing, having an open end, a shackle pivoted in said casing, a carriage removably positioned in said open end, permutation dials revolvably mounted on said carriage interiorly of 15 said casing but projecting therefrom for manual operation, tumbler disks concentric and revoluble with said dials, a locking bolt slidably positioned on said carriage for conjunctive use with said shackle, a resilient 20 means secured to said casing and normally tending to withdraw said bolt from its locked position, a tumbler carried by said locking bolt and normally abutting said tumbler disks to prevent withdrawal of said 25 bolt by said resilient means, and means formed within said disks to coöperate with said tumbler in permitting the withdrawal of said bolt.

7. In a permutation pad lock, a casing, a pivoted shackle, a locking bolt for said shackle, a supporting member within said casing, a pair of spaced revoluble dials, a

35 plate carried by said locking bolt and provided with opposite wing portions, a tumbler disk carried by each dial and adapted to rotate with the same, said dials having indicating notches upon their peripheries, said disks having corresponding recesses in their peripheries to receive the wing portions of said plate, and means for forcing 40 said tumbler outwardly to release said shackle when said recesses are opposite said wing portions.

8. In a permutation pad lock, a casing, a pivoted shackle carried by said casing, a locking bolt for said shackle, a supporting member within said casing, a pair of revoluble dials mounted on said supporting member, a tumbler disk upon the inner face of each dial, said locking bolt being movable between said disks, a plate carried by said bolt and having opposite extensions engaged with the periphery of said disks, recesses in the peripheries of said disks to receive said opposite extensions, and means 50 for forcing outwardly said bolt when said recesses are opposite said extensions.

55 In testimony whereof I affix my signature in presence of two witnesses.

OLAVIS O. VICK.
